PITCHER OR SIMILAR ARTICLE

Frank J. Benes, Lancaster, Ohio, assignor to Anchor Hocking Corporation, Lancaster, Ohio, a corporation of Delaware

Filed Nov. 1, 1968, Ser. No. 14,266

Term of patent 14 years

Int. Cl. D7—01

U.S. Cl. D44—21

FIG. 1 is a side elevational view of a pitcher or similar article showing my new design;

FIG. 2 is a rear elevational view thereof;

FIG. 3 is a front elevational view thereof; and

FIG. 4 is a top plan view.

I claim:

The ornamental design for a pitcher or similar article, substantially as shown.
